Airdyne AD Pro by Schwinn dated Oct. 2, 2015. Found online [May 13, 2016] http://www.schwinnfitness.com/schwinn_fitness_us/products/airdyne/prdcovr~100458/Schwinn+Airdyne+AD+Pro.jsp.**Primary Examiner* — Robert M Spear*Assistant Examiner* — Ryan Harvey(74) *Attorney, Agent, or Firm* — Dorsey & Whitney LLP(57) **CLAIM**

We claim the ornamental design for an exercise bike, as shown and described.

DESCRIPTION

FIG. 1 shows a top front isometric view of an exercise bike in accordance with the present design.

FIG. 2 shows a front elevation view of the exercise bike of FIG. 1.

FIG. 3 shows a rear elevation view of the exercise bike of FIG. 1.

FIG. 4 shows a left side elevation view of the exercise bike of FIG. 1.

FIG. 5 shows a right side elevation view of the exercise bike of FIG. 1.

FIG. 6 shows a top plan view of the exercise bike of FIG. 1; and,

FIG. 7 shows a bottom plan view of the exercise bike of FIG. 1.

The broken lines illustrate portions of the exercise bike that form no part of the claimed design.
